UNITED STATES PATENT OFFICE.

OSCAR O. MANN AND WILLIAM H. WHITLEY, OF GORMAN, TEXAS.

AUTOMATIC FIRE AND BURGLAR ALARM.

1,258,350.

Specification of Letters Patent.

Patented Mar. 5, 1918.

Application filed October 28, 1915. Serial No. 58,425.

To all whom it may concern:

Be it known that we, OSCAR O. MANN and WILLIAM H. WHITLEY, citizens of the United States, residing at Gorman, in the county of Eastland and State of Texas, have invented certain new and useful Improvements in Automatic Fire and Burglar Alarms, of which the following is a specification.

10 Our invention relates to alarms and more particularly to an automatic fire and burglar alarm.

The primary object of this invention resides in the provision of an improved casing in which is operatively mounted an alarm mechanism, the casing having means associated therewith for receiving a weight, the latter being preferably associated with a cord which is adapted for either attachment to a window or to a room in such a manner that, when a fire occurs the cord will burn or upon the raising of a window, the weight will move and enter the receiving means for consequently actuating the alarm mechanism.

Another object of this invention resides in the provision of an improved lever movably mounted within the casing, one end being arranged beneath the receiving or guiding hopper for receiving the weight as it falls through the hopper, the opposite end of the lever being removably associated with the alarm mechanism for releasing the trigger thereof to alarm the occupants of the building of the presence of a fire or a burglar.

Another object of this invention resides in the provision of improved spring means for association with a cord the spring means being in engagement with an actuating rod when the cord is broken or released to permit of the rod releasing the alarm from engagement with the alarm mechanism to allow the sounding of the alarm.

45 A still further object of this invention resides in the provision of a device of the character described that is simple in construction, efficient in operation and one that can be manufactured and placed on the market at a minimum cost.

50 Other objects as well as the nature, characteristic features and scope of this invention will be more readily understood from the following description taken in connection with the accompanying drawings and

pointed out in the claims forming a part of this specification.

In the drawings:—

Figure 1 is a side elevational view of our invention with the cover removed from the casing, showing the alarm after it has been released, the dotted lines illustrating the position of the lever when the alarm is inactive;

Fig. 2 is a side elevational view with the cover removed, illustrating to advantage the operation of the spring arm, the dotted lines showing the position of the arm, rod and lever preparatory to the releasing of the arm;

Fig. 3 is a top plan view of the invention with a portion of the casing removed to illustrate the arrangement;

Fig. 4 is a perspective view of the actuating rod;

Fig. 5 illustrates the means for depending the weight; and

Fig. 6 is a modified form of the alarm.

Referring more particularly to the drawings in which similar reference numerals 80 designate like or corresponding parts throughout the different views, we provide a rectangular casing 1, the casing having securing brackets 2 connected to the ends thereof for association with the wall or other support of a building through the medium of fastening devices, preferably screws 3, the outer ends of the securing brackets extending slightly beyond the front face of the casing and provided with slots 4 for removably receiving extensions 5 carried by a removable closure 6. Inward movement of the closure is limited through the medium of strips 7 secured to the inner surfaces of the ends of the casing.

Mounted within the casing is our improved alarm, in this instance constituting bell 8 removably secured to the rear wall of the casing through the medium of the screw 9. The actuating mechanism for the bell is 100 of the usual type, comprising the usual frame 10 removably secured to the rear wall through the medium of fastening devices 11. A main shaft 12 is rotatably and transversely mounted in the frame. Associated with the frame and shaft 12 is a spiral spring 13, one end thereof being rigidly connected to one side of the frame as illustrated by the numeral 14, the opposite end being rigidly connected to the shaft 110.

12 so that when the shaft is rotated through the medium of the operating key 15 on the outer screw-threaded end thereof, the spring will be wound about the shaft. Another shaft 16 is rotatably and transversely associated with the frame, said shaft having a gear wheel 17 rigidly connected thereto. A double acting pawl 18 is associated with the gear wheel 17, the pawl being carried 10 by an oscillating shaft 19 transversely mounted in the frame. A trigger 20 extends from the oscillating shaft 19 and is provided on the outer end thereof with a head 21 for contact with the bell 8. In order to 15 impart rotary movement to the shaft 16 to consequently sound the alarm, we have loosely mounted a gear wheel 22 to the shaft 12, the gear wheel being in mesh with a pinion 23 rigidly carried by the shaft 16. To 20 allow the winding of the spring 13 and prevent actuation of the shaft 16, we have rigidly connected a ratchet wheel 24 to the shaft 12, the wheel being engageable by a spring held pawl 25 pivotally associated 25 with the gear wheel 22.

The novel means for releasably controlling the actuation of the alarm in this instance comprises a lever 26 pivotally mounted intermediate its ends to a supporting 30 bracket 27, the latter in turn being rigidly connected to the bottom of the casing through the medium of suitable fastening devices 28. One end of the lever is bent at 35 right angles to the body thereof to provide a catch 29, a portion of the main body adjacent the point of distortion of the catch being provided with a recess 30 so that the angularly bent end 31 of an arm 32, extending from the oscillating shaft 17, may be arranged beneath the catch.

In order to actuate the lever 26, we have 40 mounted a receiving and guiding hopper 33 in the top of the casing adjacent the opposite end of the casing in which the bell is arranged in a manner so that the tapered 45 lower end thereof is disposed adjacent a weight receiving pan 34 carried by the free end of the lever 26. Disposed above the open end of the hopper are a plurality of weights 50 35 suspended from cords 36 each being trained about a wheel 37 and connected to various rooms in the building or to windows in the walls of the rooms, not shown. It will now be understood that when the 55 window is raised by surreptitious parties or in the event of a fire being present the raising of the window will allow the cords to slide downwardly or the fire will burn the cord and allow the weight to which the cord 60 is connected to fall down into the hopper and finally strike the receiving pan 34 which causes the catch 29 on the lever to move upwardly and release the arm 32 to consequently sound an alarm.

65 A slightly modified form for sounding the

alarm consists of a spring arm 38, one end thereof being rigidly connected to the upper surface of the top through the medium of a fastening device 39, the opposite end thereof having the cord 36 associated therewith. 70 Now when the cord moves downwardly or breaks the free end thereof will strike the head 40 of a slidably mounted actuating rod 41 in the casing, causing the rod to slide downwardly against the tension of a coil 75 spring 42 disposed thereabout and allow a lug 43 projecting therefrom to strike the operating end of the lever on which the catch 29 is formed, causing this end of the lever to be forced downwardly over the angular bent end 31 of the arm 32 and thus sound the alarm.

In Fig. 6, we have provided a fuse 44 from which depend a plurality of caps 45. This arrangement is preferably adapted for association with a chimney or other fire place so that in the event of a fire the caps 45 will explode. The fuse 44 is in connection with one of the cords 36 and when the fuse breaks one of the weights will be released 90 and thus sound the alarm.

Although we have shown and described the preferred embodiment of our invention, we desire to be understood that we are not to be limited to the exact details shown, however, we desire that great stress be laid upon the arrangement of the guiding hopper and the actuating lever 26 for association with the alarm mechanism. Attention is also directed to the arrangement of the spring arm 100 and slidably mounted actuating rod. With respect to the weights 35 it is of course to be understood that several may be employed, each being numbered to correspond to the room number to which the cord 36 is positioned. This will enable the first one to 105 reach the alarm to determine just where the fire is burning or where the burglar is present.

From the above description taken in connection with the accompanying drawings, it can easily be seen that we have provided a device that is simple in construction, containing but a few simple parts that can be cheaply manufactured and assembled and 115 when assembled can be placed upon the market and sold at a minimum cost.

It will be understood that the above description and accompanying drawings comprehend only the preferred embodiment of 120 our invention and that various minor changes in detail of construction, proportion and arrangement of the parts may be made within the scope of the appended claims and without sacrificing any of the advantages of our invention.

Having thus fully described our invention, what we claim as new and desire to secure by Letters Patent, is:—

1. An automatic fire and burglar alarm 130

including a casing, an alarm mechanism mounted therein, a lever pivotally mounted within the casing for normally retaining the alarm mechanism in an inoperative position, a weight receiving pan disposed upon one end of the lever, an operating rod means on said rod to coöperate with the lever means for releasably retaining the rod in one position, and spring means serving to move the 10 rod when released to operate said lever for permitting the alarm mechanism to sound.

2. In an automatic fire and burglar alarm, the combination with a casing and an alarm mechanism mounted therein, of a lever pivotally mounted within the casing and having one end normally serving as a catch to retain the alarm in an inoperative position, a T-shaped movable rod vertically positioned approximately at right angles to the 20 lever between the pivot and the catch end,

said rod being provided with a projection adapted to engage with the upper side of the lever, a spring serving to move the rod upward, a spring arm having one end rigidly connected to the top of the casing and its 25 other end is adapted to engage with the top of the rod, said arm being normally and releasably retained out of contact with the rod, so that when the arm is released it will drive said rod downward causing its projection 30 to move the catch of the lever to release the alarm mechanism.

In testimony whereof we affix our signatures in presence of two witnesses.

OSCAR O. MANN.
WILLIAM H. WHITLEY.
